GRID STRUCTURE FOR CATHODE-RAY TUBE

The present invention relates to improvement in an electron gun and in particular to a device or "electron optical system" used in a small electron gun for focusing an electron beam emitted from the cathode.

As is well known, numerous types of electron gun are used in cathode-ray tubes. Where it is intended to fabricate a small-sized electron gun, however, there have been found difficulties in whatsoever type of the electron gun. It is, for example, sometimes difficult to form apertures in the grid and anode electrodes aligned with the cathode. Furthermore, it is almost impossible to accurately machine and assemble such electrodes, since they should be of a small size and be positioned at a close spacing from each other and from the cathode.

It is, therefore, a primary object of the present invention to provide an improved grid structure as applicable in a small-sized electron gun.

Another object of the invention is to provide a small grid structure formed integrally with proper alignment.

Still another object of the invention is to provide an improved device or "electron optical system" used in a small electron gun for focusing the electron beam.

Other and further objects, advantages and features of the invention will be apparent to those skilled in the art from the following description, taken in conjunction with the accompanying drawings, in which:

FIG. 1 is a lengthwise section of a cathode-ray tube equipped with a conventional electron gun but dispensing with usual deflection means;

FIG. 2a is a perspective view showing the grid structure according to the present invention, which structure essentially corresponds to a portion of the electron gun shown in FIG. 1;

FIG. 2b is a section on line I—I' of FIG. 2a;

FIG. 3a is a similar to FIG. 2a but shows a modification thereof;

FIG. 3b is a section on line II—II' of FIG. 3a;

FIG. 4 is a block diagram of the electron gun equipped with the grid structure shown in FIGS. 2a and 2b;

FIG. 5 is a similar to FIG. 4 but shows another grid structure shown in FIGS. 3a and 3b;

FIG. 6a is a block diagram showing a further modified grid structure;

FIG. 6b is similar to FIG. 6a but shows a still further modified grid structure;

FIG. 7a is a lengthwise section of a still further modified grid structure;

FIG. 7b is similar to FIG. 7a but shows a still further modified grid structure;

FIG. 8a is a plan view of the grid structure as used in a color television receiver of a shadow mask type; and FIG. 8b is a fragmentary section on line III—III' of FIG. 8a.

Referring now to FIG. 1, there is shown a typical cathode-ray tube 10 using a conventional electron gun with its deflection means removed. The electron gun, as shown on the left-hand side thereof, is equipped with a plurality of metal electrodes which are shown as divided into two groups of "A" and "B" by their operations. One group "A" includes a cathode 11 and a first grid and second anode electrodes 12 and 13, respectively having apertures located substantially centrally thereof. The group "A," as a whole, acts not only as a generator of an electron beam but as focusing means providing a first beam focusing action, or "crossover" action, as is often termed. The group "B," on the other hand, includes a third, fourth, and fifth anode electrodes 14, 15 and 16, respectively, and as such functions to focus secondly and accelerate the electron beam.

The operation of the group "A" is such that the first grid electrode 12 exercises a control over the amount of the electron beam to be emitted, while the second anode electrode 13 extracts or attracts the electron beam from the cathode 11. This is because, in a conventional electron gun with a grounded cathode, the first grid electrode 12 is usually supplied with a variable negative potential, whereas the second anode

electrode 13 is maintained at a constant positive potential. In this manner, the electron beam is controlled in its emission amount by the first grid electrode 12 and is extracted by the second anode electrode 13.

Such control of the electron beam is, furthermore, considered ascribable not only to the mask action of the apertures but also to the action of repulsion forces exerted because the electron beam and first grid electrode 12 have the same polarity, i.e., the two are held at a negative potential. On the other hand, the "crossover" action of the first beam focusing action is induced by the potential field established axisymmetrically between the first grid and second anode electrodes 12 and 13, respectively.

As will be discussed at greater length hereinafter, the present invention is directed to a small-sized grid structure fabricated integrally beforehand by interposing a barrier layer between the first grid and second anode electrodes, the three layers being held in contact with each other.

In order to assist in understanding how the grid structure acts upon the electron beam, reference will now be made to FIGS. 2a and 2b and FIGS. 3a and 3b respectively showing a first and second embodiments of the invention. For the sake of simplicity of explanation, the group "A" as shown in FIG. 1 will be assumed in the following figures to be essentially similar to the grid structures and therefore like reference numerals are assigned to the parts corresponding to those in FIG. 1.

In FIGS. 2a and 2b, the grid structure comprises three concentric disc-shaped layers, i.e. a first grid electrode 17, insulator 18, and second anode electrode 19, each of which has formed centrally thereof a substantially circular aperture of a suitable inside diameter. The first grid electrode 17 is disposed closely adjacent, in a face-to-face relationship, to the cathode

11 and perpendicularly to the path of the electron beam. These first and second electrodes 17 and 19, respectively, may be made of either conductive or semiconductive materials. These material may be, for example, metal. The insulator or resistive layer 18 used as the barrier layer is tightly interposed or sandwiched between the two electrodes 17 and 19 in such a manner that all these layers or, more precisely the central apertures therein, are in alignment. However, in a practical fabrication, the grid structure is formed integrally and is thereafter chemically etched at the center thereof to form the aligned aperture of a suitable diameter.

In operation, a suitable voltage is applied from a DC voltage supply 20 across the first grid and second anode electrodes 17 and 19 so that a high potential field is established in the internal space in the aperture. As a result, there are developed symmetrically of the barrier layer 18 a plurality of electric lines of force 21, which act to bend inwardly or to focus the emitted electron beam, causing the "crossover" action. Thus, the grid structure "A" acts as such an electron beam focusing device as used in a small electron gun.

Turning to FIGS. 3a and 3b, a first grid electrode 17 is made of a P-type semiconductive material while a second anode electrode 19 is made of an N-type semiconductive material. In this modification, the barrier layer 18 is a depletion layer. Accordingly, these three layers 17, 18 and 19 form a PN-junction as a whole with the two electrodes of opposite conductivity type in electrical contact with each other.

In operation, when a reverse bias voltage is applied from a suitable DC voltage supply 20 across the P- and N-type layers 17 and 19, respectively, and if the thickness of the depletion layer 18 is not negligible over the dimensions of the apertures, then a potential field is established therein similarly to the former embodiment shown in FIGS. 2a and 2b, thus producing the beam focusing action. Therefore, detailed discussion as to its operation may be herein omitted.

In FIG. 4, there is shown a practical circuit arrangement of an electron gun equipped with the grid structure "A" of the type shown in FIGS. 2a and 2b. Across the grounded cathode 11 and first grid electrode 17 is applied from a variable DC voltage supply 22 a varying signal voltage which controls the

amount of an electron beam 23 to be emitted in response to the applied signal. On the other hand, across the cathode 11 and second anode electrode 19 is applied from a constant DC voltage supply 24 a predetermined voltage which acts to extract from the cathode 11 the electron beam 23. It, therefore, follows that the thus-controlled and focused electron beam 23 is accelerated by the remaining conventional anode electrodes 14, 15 and 16 and secondly focused into an image on the faceplate (not shown) of the cathode-ray tube.

Another modified grid structure is illustrated in FIG. 5. In this instance, across the first grid electrode 17 of P-type semiconductive material and the second anode electrode 19 of N-type semiconductive material is applied a varying signal voltage as a reverse bias voltage by a variable DC voltage supply 22, which controls the emission amount of the electron beam 23 in response to the applied signal. On the other hand, between the grounded cathode 11 and the second anode electrode 19 is supplied from a constant DC voltage supply 24 a predetermined voltage which holds the second electrode 19 at a positive potential and extracts from the cathode 11 the electron beam controlled by the first electrode 17.

Here, if the cathode is grounded as usual, it is sufficient that the first grid and second anode electrodes 17 and 19 should be held at negative and positive potentials, respectively. Hence, a number of variations thereof are conceivable without departing from the above-described principle insofar as the electrical connections are concerned.

In general, the control accuracy of the electron beam in cathode-ray tubes depends mostly on the flying distance of the electron beam as well as on the velocity thereof determined by the potential applied to the anode electrodes. As is well known, the depletion layer of a PN-junction is inherently limited in its thickness. If, therefore, it is desired to make the electron beam fly longer than the thickness of the depletion layer under the focusing influence, the barrier layer may be made thicker if a PIN- or PNPN-junction of the PN-junction as described in conjunction with FIGS. 3a, 3b and 5.

Such modified examples are illustrated in FIGS. 6a and 6b. As shown in FIG. 6a, where a PIN-junction is used, to the grounded barrier layer or an intrinsic layer 18 is connected the positive terminal of the variable DC voltage supply 22. The first grid electrode 17 of a P-type semiconductive material is connected to the negative terminal thereof, thus being maintained at a negative potential varying in response to the signal applied thereto. Across the intrinsic layer 18 and second anode electrode 19 of an N-type semiconductive material is impressed by the constant DC voltage supply 24 a predetermined voltage which holds the second electrode 19 positive. If, on the other hand, PNPN-junction is to be used as shown in FIG. 6b, the barrier layer corresponds to another internal PN-junction 18 and the N-type and P-type layers thereof are maintained at the same potential of the ground as the cathode 11. The other electrical connections are similar to the case where a PIN-junction is used.

Still other modifications of the invention are shown in FIGS. 7a and 7b, wherein a highly resistive layer 25 with a circular aperture located substantially centrally thereof is fixedly interposed between the cathode 11 and first grid electrode 17. In other words, the resistive layer 25 is mounted securely on the first electrode 17 at the opposite side of the barrier layer 18. In this manner, the grid structure according to the invention can be fabricated integrally with the cathode 11 so that more precise and easy gun alignment can be achieved. In FIG. 7b, the grid structure is comprised by a PN-junction. The arrangement of the highly resistive layer 25 is similar to that described in reference to FIG. 7a. It will be readily understood that this modification is applicable to cases where PIN- or PNPN-junction is used in the grid structure. Thus, the grid structure integrated with the cathode offers satisfactory accuracy in assembly and proper gun alignment.

The grid structure according to the invention also finds wide applications in practical multigun tubes, for example, for color television receivers of a shadow mask type, as illustrated in

FIG. 8. In this instance, the grid structure is assumed to be of the type of PIN-junction by way of example only. The letters R, G and B assigned to the grid structures are representative of the three elementary colors, i.e., red, green and blue used in a color television. The grid structures R, G and B are shown as mounted on a common substrate 26, which corresponds to N-type semiconductive material and is disposed, if desired, at the vertexes of an equilateral triangle of suitable dimensions.

In a practical fabrication of such grid structures, intrinsic layers are first produced, for example, by "diffusion method" at predetermined positions in the N-type substrate or the second anode electrode, on which are then produced by the similar method respective P-type layers or first grid electrodes. Upon completion of such processing, suitable central apertures are formed in the resultant layers for admitting the electron beams representing the color signals, i.e., red, green and blue. With these arrangements, if variable signal voltages are applied as reverse bias voltage across the common second electrode and the respective first electrodes, all of the grid structures R, G and B can be controlled independently of one another.

As will be easily understood, the PIN-junction used in this modification can be replaced by all of the aforementioned embodiments. Where semiconductive materials such as PN- or PNPN-junction are employed for the grid structures, similar method and arrangement may be employed for the same purposes so that a detailed discussion may be omitted. However, where the grid structures are made of conductive materials as electrodes and of an insulator as a barrier layer, as described with reference to FIGS. 2a, 2b and 4, the common substrate should be made of any highly resistive material, in which are embedded the respective grid structures.

It will now be apparent from the foregoing description that the combinations and arrangements of the grid structure as herein disclosed may be varied without departing from the concept of the present invention. Thus, it will be understood that the embodiments of the inventive concept illustrated herein is exemplary and not limitative, since modifications and variations thereof, some of which have been pointed out hereinabove, may be made without departing from the spirit and scope of the invention as claimed in the appended claims.

What is claimed is:

1. In a cathode-ray tube having a cathode, a grid structure for focusing an electron beam generated from said cathode comprising a first layer of grid electrode with a circular aperture formed substantially centrally therein, which layer is disposed in a face-to-face relationship closely adjacent to said cathode and perpendicularly to the path of said beam for controlling the amount of the electron beam to be emitted in response to the variation in the electric potential applied thereto, a second layer of anode electrode with a circular aperture formed substantially centrally therein, which layer is disposed closely adjacent to and in alignment with said first electrode for extracting the electron beam by the action of the electric potential applied thereto, and a barrier layer with a circular aperture formed substantially centrally therein, which layer is interposed fixedly between said first and second layers for electrically isolating the same from each other, the apertures in said first, second and barrier layers being in alignment with one another and held in coaxial relationship with said cathode, whereby the electron beam passing through said apertures is focused under the influence of the potential field established axisymmetrically within said apertures due to the difference in the potentials applied to said two first and second layers.

2. A grid structure according to claim 1, wherein said first and second layers are made of a conductive material and said barrier layer is made of a highly resistive material.

3. A grid structure according to claim 2, wherein said conductive material is metal.

4. A grid structure according to claim 1, wherein said first and second layers are made of a semiconductive material and said barrier layer is made of a highly resistive material.

5. A grid structure according to claim 4, wherein said first layer is made of a P-type material, said second electrode is made of an N-type material and said barrier layer is a depletion layer, thereby forming a PN-junction as a whole by bringing said first and second layers of opposite conductivity type into electrical contact.

6. A grid structure according to claim 4, wherein said first layer is made of a P-type material, said second layer is made of an N-type material and said barrier layer is an intrinsic layer, thereby forming a PIN-junction as a whole by bringing said first and second layers of opposite conductivity type into electrical contact.

7. A grid structure according to claim 4, wherein said first layer is made of a P-type material, said second layer is made of an N-type material and said barrier layer is constituted generally of a PN-junction N-type layer of which is made contact with said first layer and P-type layer of which is made contact with said second layer, thereby forming a PNPN-junction as a whole by bringing said first and second layers of opposite conductivity type into electrical contact.

8. A grid structure according to claim 2, further comprising a highly resistive layer with a circular aperture formed substantially centrally therein, which resistive layer is fixedly interposed between said cathode and said first layer for electrically isolating said cathode and said first layer from each other in such a manner that the apertures in all of said layers are in alignment with each other and held in coaxial relationship with said cathode.

9. A grid structure according to claim 4, further comprising a highly resistive layer with a circular aperture formed substantially centrally therein, which resistive layer is fixedly interposed between said cathode and said first layer of semiconductive material for electrically isolating said cathode and said first layer from each other in such a manner that the apertures in all of said layers are in alignment with each other and held in coaxial relationship with said cathode.

10. A multigun tube comprising at least two of said grid structures according to claim 2, which grid structures are embedded in a common substrate made of a highly resistive material, wherein the electron beams emitted from the respective cathodes and admitted through the respective apertures are focused independently of one another.

11. A multigun tube according to claim 10, wherein said multigun tube is of shadow mask type and is used for a color television receiver with said grid structures positioned at the vertexes of an equilateral triangle.

12. A multigun tube comprising at least two of said grid structures according to claim 4, which grid structures are embedded in a common substrate made of a highly resistive material, wherein the electron beams emitted from the respective cathodes and admitted through the respective apertures are focused independently of one another.

13. A multigun tube according to claim 12, wherein said multigun tube is of shadow mask type and is used for a color television receiver with said grid structures positioned at the vertexes of an equilateral triangle.

14. A multigun tube comprising at least two of said grid structures according to claim 2, which grid structures have a common substrate made of a conductive material on which are respectively mounted highly resistive layers on which are further mounted respective conductive layers, wherein the electron beams emitted from the respective cathodes and admitted through the respective apertures are focused independently of one another.

15. A multigun tube according to claim 14, wherein said multigun tube is of shadow mask type and is used for a color television receiver with said respective grid structures positioned at the vertexes of an equilateral triangle.

16. A multigun tube comprising at least two of said grid structures according to claim 4, which grid structures have a common substrate made of a semiconductive material on which are respectively produced barrier layers on which are further produced respective semiconductive layers, wherein the electron beams emitted from the respective cathodes and admitted through the respective apertures are focused independently of one another.

17. A multigun tube according to claim 16, wherein said multigun tube is of shadow mask type and is used for color television receivers with said respective grid structures positioned at the vertexes of an equilateral triangle.

18. An electron beam focusing device comprising said grid structure according to claim 2, wherein a variable DC voltage is applied across said cathode and said first layer which is maintained at a varying negative potential and a constant DC voltage is applied across said cathode and said second layer which is maintained at a predetermined positive potential.

19. An electron beam focusing device comprising said grid structure according to claim 4, wherein a variable DC voltage is applied across said cathode and said first layer which is maintained at a varying negative potential and a constant DC voltage is applied across said cathode and said second layer which is maintained at a constant positive potential.
